2 Claims

ABSTRACT OF THE DISCLOSURE

An attachment for applicable and removable use (FIG. 1) when one desires to hold and drink from a punctured beer or soft drink can. It comprises a length of metal or plastic strap, one end having a U-shaped clamp with bead-held snap-on lugs, the other end having an oriented handgrip.

The present invention relates to certain new and useful improvements in a readily attachable and detachable can handling attachment which is expressly and suitably designed for use when picking up, handling and also while holding and drinking from a can, for example, a beer or beverage can having a puncturable top and which, as is usually the case is also provided with an endless or encircling top retaining bead.

Briefly the attachment is characterized by an elongated strap member having (1) a substantially U-shaped can clamping holder at one end capable of being saddled over the puncturable top of said can and (2) an integrally attached handgrip at its other end, said handgrip being disposed at an angle lateral to the over-all lengthwise dimension of said clamp in a manner to occupy a readily grippable and usable position along an adjacent side of said can.

An object of the invention is to structurally, functionally and in other significant ways improve upon similarly constructed and performing handling and holding means for cans and the like, for example the detachable can handle disclosed in the patent to Wiedemann, 2,075,685.

Unlike prior Patent 2,075,685, the present invention, as above suggested, is manufactured or made from a single length of appropriate strap stock or material which can be formed to provide the clamp means at one end and the handle means at the other end.

In carrying out the principles of the present invention the strap member from which the over-all attachment is made is bent upon itself in such a manner that one end portion is elongated generally U-shaped to provide a clamp which can be readily snapped over the end of the can to bridge and attach itself to the can, the other end being formed into a simple curvate conveniently usable handle or handgrip.

More specifically, novelty is predicated on a simple one piece attachment wherein the U-clamp embodies a bight portion which bridges and spans the selected end (usually the top) of the can, said clamp being unique in that the depending oppositely disposed generally parallel legs at the end portions have terminal ends which in turn are provided with suitably paired outstanding lugs. To the ends desired, the lugs not only can be readily snapped into place, they underlie the overhanging bead to, in this manner, assist in positioning and retaining the clamp after it has been applied. It follows that the thus lug-equipped clamp functions not only to retain itself securely and effectually hold the can but positions the handle or handgrip so that it may be conveniently utilized.

These together with other objects and advantages which will become subsequently apparent reside in the details of construction and operation as more fully hereinafter

2

described and claimed, reference being had to the accompanying drawings forming a part hereof, wherein like numerals refer to like parts throughout, and in which:

FIG. 1 is a view in perspective of a beer can or the like having a punctured top, said view showing the attachment characterized by the aforementioned lug-equipped U-clamp and the readily and conveniently useable handgrip.

FIG. 2 is a central longitudinal sectional view through the over-all attachment with the can shown in phantom lines.

FIG. 3 is a bottom plan view.

Referring now to the views of the drawing and in particular to FIG. 1 it will be seen that the beer or beverage can or equivalent container is denoted by the reference character A, the same having duplicate ends. The upper end in FIG. 1 is designated as the top as at B and is shown provided with a marginal depending and reinforcing rim or bead C. It can be assumed in this discussion of the view that the top has been punctured in one manner or another to provide a pouring hole as at D.

The attachment, as already set forth, is formed from a single length of strap metal which may be made of an appropriate grade of metal or plastic material as desired by the manufacturer. One end portion is formed or fashioned into a generally U-shaped attaching and holding clamp which is denoted by the numeral 6. This clamp comprises a generally flat straight bight portion 8 which bridges or spans the top of the can. One laterally directed leg which may be referred to as the left leg in FIG. 2 is denoted by the numeral 10, the opposite slightly longer leg being denoted by the numeral 12. These legs are adapted to depend along diametrically opposite side portions of the body of the can. The leg 10 is provided at its lower free end with a pair of companion outstanding leg positioning and orienting lugs which are denoted at 14 each lug being generally rectangular and said lugs underlying the overhanging bead C in the manner shown in FIG. 2. The leg 12 is likewise provided with a pair of outstanding companion lugs 16, said lugs being suitably curved to effectually embrace that portion of the can contacted thereby and as shown in the views of the drawing. The aforementioned handle or handgrip is approximately J-shaped in edge elevation and is denoted by the numeral 18 and is appropriately curved and of suitable length and is disposed in a plane at approximate right angles to the horizontal plane of the clamp 6, that is when in use. The upper curvate end portion 20 of the handle is joined by an appropriate bend or bent portion 22 to the lower end of the leg 12 below the level of the two lugs 16. The lower free or terminal end portion of the handgrip is denoted at 24 and is usually, but not necessarily, spaced from the surface of the can in the manner illustrated in FIGS. 1 and 2.

In practice it will be obvious that the U-clamp 6 is such in construction that it can be readily snapped into place to assume the position illustrated in FIG. 1. To the ends desired the bight portion 8 spans or bridges the top B of the can while the legs 10 and 12 straddle the diametrically opposite side portions of the can. Accordingly the clamp may be said to be saddled removably on the can. It is stabilized and securely held when the paired lugs 14 at the left and 16 at the right embrace the can and assume retaining positions underneath the overlying edge or shoulder of the bead C. Once the clamp is in place in the manner illustrated the handle means 18 is effectually positioned whereby the user can pick up, handle and effectually hold the can, whether it be hot or cold and can either pour the contents, or in the case of cold drinks, can drink directly from the can in a now generally well-known manner.

What is claimed as new is as follows:

1. For use when picking up, handling and also while holding and drinking from a beer can or similar beverage containing can having a puncturable top with an encircling and mounting bead, a readily attachable and detachable can handling attachment comprising: an elongated one-piece flat-faced strap member having two component parts, namely, a substantially U-shaped clamp and a companion handgrip, said clamp embodying a straight bight portion of a length that is capable of bridging and spanning a median restricted portion of the top of the can in a manner to be out of the way of that portion of the top which is to be punctured for pouring or drinking, as the case may be, further including a first lateral depending leg which is adapted to overhang and depend below the aforementioned bead, said first leg having a free end provided with a pair of integral lateral outstanding clamp positioning and retaining lugs, said lugs being arcuately curved and adapted to conformingly embrace the peripheral surface portion of the can with which they are adapted to cooperate, said lugs having straight upper edges which are adapted to underlie a segmental shoulder portion of the overhanging bead, said clamp further including a second depending leg opposed and substantially parallel to said first leg, said second leg being likewise provided with a pair of integral lateral outstanding lugs which cooperate with the first-named lugs in positioning and retaining said clamp and being arcuately bowed to contact the surface of the body of the can and also having straight

coplanar upper edges designed and adapted to underlie and engage a segmental edge of the aforementioned bead, said handgrip being in a plane approximately at right angles to the lengthwise dimension of said bight portion and being oriented with and connected to said second depending leg.

2. The can handling attachment defined in and according to claim 1 and wherein said handgrip is substantially J-shaped in edge elevation, said handgrip having an upper end which is joined to a cooperating lower end of said second leg by a bent portion which functions to locate the handgrip in a readily usable position relative to the clamp and the can.
